(57) **CLAIM**

The ornamental design for an insect catching funnel shaped lid for disposable cup, as shown and described.

DESCRIPTION

FIG. 1 is a top perspective view of an insect catching funnel shaped lid for a disposable cup;

FIG. 2 is a bottom perspective view of the insect catching funnel shaped lid in FIG. 1;

FIG. 3 is a top plan view thereof;

FIG. 4 is a bottom plan view thereof;

FIG. 5 is a side elevation view thereof;

FIG. 6 is a front elevation view of the insect catching funnel shaped lid fitted over the top rim of a disposable cup;

FIG. 7 is a top perspective view of an insect catching funnel shaped lid for a disposable cup showing a second embodiment of the design;

FIG. 8 is a bottom perspective view of the insect catching funnel shaped lid in FIG. 7;

FIG. 9 is a top plan view thereof;

FIG. 10 is a bottom plan view thereof;

FIG. 11 is a side elevation view thereof; and,

FIG. 12 is a side elevation view thereof with the cover on the nozzle.

The back elevation view and the side elevation view are substantially as shown in the front elevation view.

The broken lines in FIGS. 6 and 12 illustrate the cup on which the insect catching funnel shaped lid is placed and is shown to depict the environment in which the lid is used. The broken lines in FIGS. 7–10 depict optional holes that can be formed on the top side of the insect catching funnel shaped lid and are for illustrative purposes. None of the broken lines form a part of a part of the claimed design.
